UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

HEMMING OR WELTING MACHINE.

Application filed December 2, 1925. Serial No. 72,710.

The invention relates to new and useful improvements in sewing machines, and more particularly to a sewing machine for forming a welt or hem in a knitted fabric, such as a stocking or the like.

An object of the invention is to provide a machine of the above type wherein the body portion of the fabric is folded to form a hem, and is again folded to lay the hem back on the body portion of the fabric so that the folded edge between the hem and the body portion of the fabric can have stitches passed therethrough which are substantially concealed from view on the right face of the fabric, with means for inturning the extreme edge of the material so that it is concealed in the finished hem or welt.

Another object of the invention is to provide a machine of the above type with a trimming mechanism for trimming the edge of the material prior to the inturning of the same.

A further object of the invention is to provide a machine of the above type with a yielding pressing member separate from the usual presser foot, which bears upon the portion of the fabric which is to be trimmed and infolded, and which also guides the edge of the fold in the body of the fabric, which member is capable of yielding to permit the finishing of the hem or welt when welting a circular article, such a stocking top.

A further object of the invention is to provide a machine of the above type with means for raising the portions of the fabric adjacent the fold between the body portion of the fabric and the welt, infolding the edge portion and subsequently turning the fold in the body portion down on to the infold of the edge portion and stitching the same.

These and other objects will in part be obvious and will in part be hereinafter more fully disclosed.

In the drawings which show by way of illustration one embodiment of the invention—

Figure 1 is a front view of a machine embodying my invention;

Fig. 2 is an end view of the same with parts broken away to show the looper support;

Fig. 3 is a view in plan of a portion of the work support, also showing the presser foot and the auxiliary yielding member associated therewith;

Fig. 4 is a view of a portion of the cloth plate on a larger scale, showing the parts directly associated with the cloth plate, and

with the presser foot and spring member removed;

Fig. 5 is a section on the line 5—5 of Fig. 3;

Fig. 6 is a sectional view on the line 6—6 of Fig. 3; with certain parts omitted;

Fig. 7 is an edge view of the throat plate and the parts directly carried thereby as viewed from the right-hand side of the throat plate;

Fig. 8 is a perspective view of the bracket rigidly secured to the throat plate and carrying a strip deflector, a stitch finger and a guide for directing the upper folded portion of the fabric;

Fig. 9 is a side view of the yielding member associated with the presser foot;

Fig. 10 is a bottom plan view of the same;

Fig. 11 is a sectional view at a point in front of the trimmer showing the presser foot and the yielding member;

Fig. 12 is a similar view, but taken in rear of the trimming mechanism;

Fig. 13 is a similar view, but taken still further back from the trimming mechanism and showing the means for raising the edge of the fold in the body portion of the fabric, and the means for infolding the edge portion of the fabric;

Fig. 14 is a similar view, but still further back toward the needle, and showing the edge portion as completely infolded, and

Fig. 15 is a similar view at the stitching point, and showing the fold in the body portion of the fabric and the infolded edge as superposed and held so that the needle will stitch these parts together in such a manner that the stitches which unite the parts will be substantially concealed from view on the face of the fabric.

The invention is directed broadly to a machine for forming a welt or a hem in a knitted fabric, and more particularly for forming a welt for circular articles, such as stockings.

The machine in its present embodiment includes a vibrated needle and a threaded looper which cooperates with it. The article to be stitched is folded so as to form a hem, and then the hem is folded back on the body portion of the fabric. The article so folded is led into the machine. The folded portion of the fabric between the hem or welt and the body portion of the fabric, is led underneath the presser foot, while the edge portion of the fabric which is not folded is led underneath

the yielding member which holds the same down on the section of the feed dog, so as to insure proper feeding of this edge portion of the body fabric. A trimming mechanism 5 is located in the machine so as to trim this edge portion of the fabric which has not been folded when it is led into the machine, and a suitable strip guide deflects the cut off edge to one side away from the stitching mechanism. Located in front of the throat plate 10 is an uncurler for uncurling the edge prior to the trimming of the edge. The yielding member which holds the uncurled lower edge portion against the section of the feed dog, 15 also serves as an edge guide for the edge of the fold between the body portion of the fabric and the welt, and further serves to lift the folded edge portion from the unfolded portion beneath the same. After the edge of 20 the fabric has been trimmed, it passes through a folder which inturns the trimmed edge portion, and this folder is so disposed as to inturn said edge portion and lay the inturned part on the upper face of said lower portion which is trimmed while the folded 25 edge portion is raised. After this part has been infolded, then the raised folded edge portion is laid down on said inturned edge and superposed thereon. The fabric as thus 30 folded is fed to the stitching mechanism. The stitching mechanism is so positioned relative to the folds in the fabric, that the needles on one stroke will pass through the folded edge between the body portion of the fabric and 35 the welt or hem, and the needle, in its descent, will pass into and out of the fabric on the same face thereof without passing through to the other face of the fabric. In other words, the needle makes a blind stitch, 40 or stitches which are at least substantially concealed from view on the right face of the material. On the next stroke of the needle, it passes over the edge of the infolded portion, so that said infolded outer edge of the 45 hem fold is joined to the body portion of the fabric by the stitches. The hem or welt thus stitched, when folded out, has the free edge portion and the edge thereof concealed.

Referring more in detail to the drawings, 50 my improved machine for hemming or weltting knit fabric consists of a work support 1 mounted on a suitable bed plate 2. The machine includes an overhanging arm 3 and a needle lever 4. Mounted on the free end of 55 the overhanging arm 3 is a needle bar supporting gate 5 in which the needle bar 6 reciprocates. The needle bar carries a needle 7. The needle bar supporting gate 5 is mounted to oscillate freely on the support 8 carried by the overhanging arm. Said needle gate is provided with the usual arm 9 which is connected by a link 10 with a rock arm 11 fixed to a rock shaft 12. This rock shaft is oscillated and imparts a vibration to the gate, 60 thus causing the needle on one stroke to enter the material, and on its next stroke to pass over the edge of the material. This is an ordinary vibrated needle. Cooperating with the needle beneath the work support is a threaded looper 13. This looper cooperates 70 with the needle on both of its strokes through and over the edge of the material, and thus the needle thread loops are joined beneath the material. Inasmuch as the needle vibrates from one stroke to the other, the needle 75 thread covers the upper face of the material between successive stitches of the needle, and therefore, in the present embodiment of the invention, where the edge portion is being blind-stitched to the body fabric, the edge is 80 encircled and covered by the threads forming the stitches.

In Figures 11 to 15 of the drawings I have shown more or less diagrammatically the steps through which the fabric passes in the forming of the welt or hem. Brief reference will be made thereto, as the invention will be more easily understood with a knowledge of what is sought to be accomplished. The knitted body fabric is indicated at 14 in these 90 figures of the drawings. Said knitted fabric is first folded back at the point 15 to prepare the fabric for the welt or the hem. Then the fabric is again folded at 16 in order to lay the welt or hem thus formed back against the 95 face of the body fabric. The under layer 17 of the welt or hem projects beyond the fold at 16 as indicated at 18 in Fig. 11. The fabric folded as above stated, is led into the machine, and passes beneath the presser foot 19, 100 and also the yielding member 20 located alongside of the presser foot. These two yielding parts bearing on the fabric hold the fabric in proper cooperative relation with the feed dogs of the machine, so that the 105 folded fabric is fed beneath the presser foot and yielding member 20. The under layer 17 of the welt or hem passes entirely underneath the yielding member 20 and to the right thereof as viewed in Fig. 11. The fold 16 in 110 the body fabric passes along the face of the yielding member 20 and is raised by the beveled surface 21 at the front end of the yielding member 20, and a curved recess 22 in the side face of said yielding member 20. The 115 presser foot is cut away as indicated at 23 in order to allow this raising of the folded portion of the fabric. As the fabric passes along through the machine, it is first operated upon by a trimming mechanism including a movable trimming blade 24 and a stationary trimming blade 25. This trimming mechanism trims off the edge of the lower layer 17 of the hem. After passing the trimming mechanism, the edge of the lower layer 120 of fabric passes into a folder 26 which curls said lower edge so as to turn it upwardly and inwardly and finally infold the edge of said lower layer 17 of the fabric. During this infolding of the lower edge, the folded portion 125 130

16 is raised to a greater extent, and the infolded portion is tucked underneath this raised folded portion. After the infolded edge has been placed under the folded portion, then the folded portion is pressed down on top of the infolded edge, and the fabric is presented to the needle for stitching. The needle 7 when at its left hand reciprocating position, will pass through the upper layer 10 of fabric at the fold therein, and as a matter of fact, the needle will enter and emerge on the same face of the fabric without going through to the other side thereof. If it does go through to the other face thereof it is very slight, and therefore, the stitches formed on this stroke of the needle will be concealed from view on the right face of the fabric. The needle, when at its right hand reciprocating position, as indicated at 7^a in Fig. 15, 20 will pass over the edges of the folds in the fabric and on the opposite side of a stitch finger 27 so that the needle thread will be laid over this stitch finger and the needle loops, when joined by the looper thread, will 25 encircle the stitch finger, and will be fed off from the free end thereof.

The presser foot 19 is carried by a presser bar 28 which is of the usual construction. The upper movable trimming blade 24 is carried by a cross-head 29 which reciprocates on a fixed rod or shaft 30 secured to a bracket carried by the overhanging arm. Said cross-head is raised and lowered on said rod by means of an oscillating shaft 31 which oscillating shaft carries an arm 32 connected by means of a pin 33 to an arm 34 carried by a sleeve 35 loosely mounted on the shaft 31, and this arm 34 is in turn connected by a link 36 to a stud on the cross-head 29. The trimming blade 24 is carried by a bracket arm 37 which is secured to the cross-head by means of a bolt 38 passing through an elongated slot 40. This provides a means for adjustment of the trimming blade. The pin 33 may be withdrawn from its connection to the arm 34, and when so withdrawn, the spring 41 will raise the cross-head and the trimming head carried thereby to inoperative position. This trimming mechanism forms no part of the present invention, and further description thereof is not thought necessary.

The yielding member 20 is shown more fully in Figures 3, 9 and 10. This yielding member 20 is secured to the throat plate 42 by screws 43, 43. These screws pass through slots in the yielding supporting portion of the member 20 and permit the member to be adjusted in a direction parallel with the line of feed. The forward end of this spring member 20 is provided with a foot portion 44 which overlies the section 45 of the feed dog. The sections 46 and 47 of the feed dog cooperate with the presser foot 19. This yielding member 20 has a beveled portion 21 65 at the forward end thereof, which aids in the

raising of the fold 16 in the body fabric. It also has a curved recess 22 in the side face thereof. Said foot portion 44 of the yielding member 20 is also provided with a rearwardly projecting toe 48 (see Figures 9 and 10). This toe 48 is tapered on one side thereof. The other side of the toe adjacent the needle is substantially parallel with the line of feed. This toe is to aid in the infolding of the trimmed portion of the fabric. The folder 26 is carried by a shank 49 which is secured to the throat plate of the machine by means of a screw 50 (see Fig. 7), which passes up through the throat plate 42 and threads into the shank 49. The right-hand side of the member 20 is formed with a straight wall 51 which lies along the side of the slot 52 formed through the yielding member 20 which holds the material while trimming. Directly in rear of this foot portion 44 of the yielding member 20 is a folder 26. This folder 26 has a vertical wall 53 alongside of which the trimming blade operates, and a strip deflector 54 which projects at an angle to the line of feed, and directs the trimmed off strip away from the folder and the stitching mechanism. The trimmed edge passes into the scroll 55 of the folder 26, and the edge is inturned. The folder also has a recess 56 in the side face thereof adjacent the needle, which cooperates with the curved side face 22 of the yielding member 20 in the raising of the folded portion 16 of the fabric. The toe 48 extends into the scroll portion 55 of the folder (see Fig. 13), and holds the trimmed edge portion of the fabric down while the scroll folds the inturned portion thereof over this toe. As clearly shown in Figures 13 to 15, the inturned portion of the trimmed edge is folded back, while the folded portion 16 is held raised so that the inturned part of the infolded portion is laid beneath this raised portion 16. The presser foot has a cut-away part 23, as noted which allows this raising of the folded portion 16. This cut-away portion 57 gradually vanishes, and the raised portion is forced down on to the infolded portion. The folder is also provided with a laterally projecting guiding finger 58 which overlies the portion 16 of the folded fabric. This finger serves as a guide for the edge of this folded portion. The presser foot 19 has a cut-away portion 60 for the needle. The folder 26 is also provided with a stitch finger and edge guide 27 which serves to guide the edges 120 of the fabric as it is being stitched, and the overedge stitches are laid over this finger. As the needle vibrates laterally, first it passes one side of the stitch finger, and through the opening in the side face of the presser foot, and then the other side of the stitch finger and through an opening in the yielding member 20. Directly in front of the throat plate is an uncurler 62 which is secured to the work support by means of a screw 63. Said uncurler 130

curler has a curved raised portion 64 and a rearwardly projecting inclined finger 65. This inclined finger 65 extends underneath the front end of the foot portion 44 which is tapered at 66 to provide clearance therefor. The purpose of this uncurler and guiding finger is to uncurl the edge of the fabric and pass it rearwardly in flat condition to the trimmer.

10 It is thought that the operation of the machine will be fully understood from the detail description which has been given of the parts which cooperate in the forming of the welt and the blind-stitching of the same. While 15 I have described in detail a vibrated needle for forming the edge covering stitches, it will be understood that other types of overseaming mechanisms may be used for this purpose. The essential features of this invention reside 20 in the particular way in which the fabric is handled, trimmed and infolded to provide a welt which can be stitched in such a way that the stitches are concealed from the face side of the fabric, and the infolded trimmed edge 25 portion of the fabric covered by the stitches.

It is obvious that minor changes in the details of construction and the arrangement of the parts may be made without departing from the spirit of the invention as set forth 30 in the appended claims.

Having thus described the invention, what I claim as new and desire to secure by Letters-Patent, is—

1. In a sewing machine, the combination 35 of stitching mechanism, a presser foot, feeding mechanism, a yielding member located at one side of the presser foot and bearing on the material in advance of the presser foot, said yielding member having a foot portion for guiding the edge of a fold formed by the laying of a hem fold back on the body portion of the goods, the edge portion of the goods forming the hem fold extending underneath said yielding member, and means 40 for inturning the edge portion of the material so that the edge thereof is concealed in the finished hem.

2. In a sewing machine, the combination 50 of stitching mechanism, a presser foot, feeding mechanism, a yielding member located at one side of the presser foot and bearing on the material in advance of the presser foot, said yielding member having a foot portion for guiding the edge of a fold formed by the laying of a hem fold back on the body portion of the goods, the edge portion of the goods forming the hem fold extending underneath said yielding member, means for inturning the edge portion of the material so that the edge 55 thereof is concealed in the finished hem, and a trimming mechanism operating upon the edge portion of the material forming the hem fold for trimming the same prior to the infolding thereof.

3. In a sewing machine, the combination of

stitching mechanism, a presser foot, feeding mechanism, a yielding member located at one side of the presser foot and bearing on the material in advance of the presser foot, said yielding member having a foot portion for 70 guiding the edge of a fold formed by the laying of a hem fold back on the body portion of the goods, the edge portion of the goods forming a hem fold extending underneath said yielding member, and means for 75 inturning the edge portion of the material so that the edge thereof is concealed in the finished hem, said guiding means for the edge of the fold being so disposed relative to the stitching mechanism that the needle passes 80 into and out of the body portion of the fabric on the same face thereof, thus forming blind stitches.

4. In a sewing machine, the combination of 85 stitching mechanism including a vibrated needle, a presser foot, feeding mechanism, a yielding member alongside of said presser foot and extending to a point in advance thereof, said yielding member having a foot portion with a rearwardly projecting toe 90 adapted to direct a body fabric having the hem fold therein laid back on said body portion, said foot portion operating to guide the edge of the fold in the body fabric while the edge portion of the hem fold projects 95 underneath said foot portion, a folding scroll in rear of the foot portion of said yielding member into which said toe projects, said scroll operating to inturn the edge portion of the hem, and a trimming mechanism 100 operating to trim said edge portion prior to the infolding thereof.

5. In a sewing machine, the combination of 105 stitching mechanism including a vibrated needle, a presser foot, feeding mechanism, a yielding member alongside of said presser foot and extending to a point in advance thereof, said yielding member having a foot portion with a rearwardly projecting toe 110 adapted to direct a body fabric having the hem fold therein laid back on said body portion, said foot portion operating to guide the edge of the fold in the body fabric while the edge portion of the hem fold projects underneath said foot portion, a folding scroll in 115 rear of the foot portion of said yielding member into which said toe projects, said scroll operating to inturn the edge portion of the hem, and a trimming mechanism operating to trim said edge portion prior to the infolding thereof, said foot portion of said yielding member and said presser foot being shaped so as to raise the edge of the fold between the body fabric and the hem fold while the inturned edge is laid beneath the same. 120

6. In a sewing machine, the combination of 125 stitching mechanism, a presser foot, a feeding mechanism, means for guiding a body fabric having a hem fold folded back on the body fabric beneath the presser foot, said means 130

including devices for lifting the portion of said body fabric and hem fold adjacent the fold in the body fabric, said devices being disposed alongside of the presser foot, and devices for inturning the edge portion of said hem fold so that said inturned edge portion is laid beneath the lifted portion of the body fabric, said presser foot being shaped so as to permit the lifting of said portion and for subsequently returning said lifted portion of the body fabric on to said inturned edge portion whereby said inturned edge portion is secured to the body fabric by stitches and the edge of the fabric concealed within the finished hem.

7. In a sewing machine, the combination of stitching mechanism, a presser foot, a feeding mechanism, means for guiding a body fabric having a hem fold folded back on the body fabric beneath the presser foot, said means including devices for lifting the portion of said body fabric and hem fold adjacent the

fold in the body fabric, said devices being disposed alongside of the presser foot, and devices for inturning the edge portion of said hem fold so that said inturned edge portion is laid beneath the lifted portion of the body fabric, said presser foot being shaped so as to permit the lifting of said portion and for subsequently returning said lifted portion of the body fabric on to said inturned edge portion whereby said inturned edge portion is secured to the body fabric by stitches and the edge of the fabric concealed within the finished hem, said stitching mechanism including a laterally vibrated needle disposed so as to pass on one stroke into and out of the body fabric on the same face thereof, and on its next stroke so as to pass clear of the body fabric at the fold therein, whereby said inturned edge portion is secured to the body fabric by blind stitches.

In testimony whereof, I affix my signature.
JAMES R. MOFFATT.
